DESIGN FOR A TOY

Clyde S. Payne, Jr., North Hollywood, Calif.

Application April 19, 1940, Serial No. 91,781

Term of patent 3½ years

To all whom it may concern:

Be it known that I, Clyde S. Payne, Jr., a citizen of the United States of America, residing at North Hollywood, county of Los Angeles, and State of California, have invented a new, original, and ornamental Design for a Toy, of which the following is a specification, reference being had to the accompanying drawing, forming part thereof.

Fig. 1 is a side view of the toy showing my new design.

Fig. 2 is a front view of the toy.

Fig. 3 is a top plan view of the toy.

Fig. 4 is a rear view of the toy.

I claim:

The ornamental design for a toy, as shown.

CLYDE S. PAYNE, JR.
